UNITED STATES PATENT OFFICE.

SEBASTIANO MAGNANO, OF LAWRENCE, MASSACHUSETTS, ASSIGNOR TO MAGNANO CORPORATION, OF ESSEX, MASSACHUSETTS, A CORPORATION OF MASSACHUSETTS.

HARNESS STOP AND SIGNAL DEVICE FOR LOOMS.

Application filed June 15, 1923. Serial No. 645,539.

To all whom it may concern:

Be it known that I, SEBASTIANO MAGNANO, a subject of the King of Italy, and resident of Lawrence, in the county of Essex and 5 State of Massachusetts, have invented new and useful Improvements in Harness Stop and Signal Devices for Looms, of which the following is a specification.

This invention concerns textile machinery 10 and relates more particularly to automatic stopping and indicating means applicable to weaving looms and the like wherein a harness mechanism is employed, the present application being a continuation in part of my 15 copending renewed application Serial No. 548,522, filed March 31, 1922.

In automatic looms as commonly constructed there is provided a stop motion mechanism which is operative automatically 20 to stop the loom upon the breakage or failure of the filling or upon the breakage of the warp threads. The provision of such a mechanism provides to a considerable extent against the formation of defective cloth, 25 but it is found that in the operation of looms, particularly those employing a large number of harnesses under the control of pattern mechanism, defective cloth is often produced by the failure of one or more of 30 the harnesses to move in properly timed relation to the other harnesses.

While the defects produced by failure or breakage of the warp or weft threads are readily detected, it is much less easy in 35 many cases, to detect improper weave resulting from failure of a harness to move in the predetermined order, and the principal object of the present invention is to provide means whereby to avoid defects in the fabric 40 arising from such failure of a harness properly to function. To this end it is proposed to provide mechanism, cooperable with the usual stop motion employed in automatic looms, and having proper connections with 45 the individual harnesses, whereby, upon failure of one or more of the latter properly to function, the stop motion mechanism will be energized.

As the number of harnesses employed in a 50 loom may be quite large, as many as forty being sometimes employed, it is obvious that upon stoppage of the loom it is desirable for

the workman to determine without delay the particular harness which is functioning improperly. A further object of the present 55 invention is to provide signaling means, preferably consisting of a lamp, to indicate the defective harness when the loom stops.

A preferred embodiment of means for carrying the invention into effect is disclosed 60 in the accompanying drawings, in which,—

Fig. 1 is a side elevation, partly in section and partly diagrammatic, illustrating means for initiating the operation of the stop mechanism of the loom and for giving a visual 65 signal upon the defective operation of a harness;

Fig. 2 is a fragmentary end elevation from the right hand side of fig. 1, illustrating certain details of construction; and 70

Figs. 3 and 4 are diagrammatic views corresponding to figs. 1 and 2, and illustrating the electrical circuits employed.

Referring to the drawings the numeral 1 indicates a pinion receiving its motion from 75 the loom mechanism and in timed relation to the usual pattern mechanism which may be employed therein and which is not herein shown. It is to be understood in this connection that the present apparatus is applicable 80 to any of the ordinary and well known forms of loom employing pattern controlled harness mechanism, and it is thus considered unnecessary to disclose the specific arrangement of parts included in such machines. 85

The pinion 1 drives a gear 2 carried upon a pattern shaft 3. This shaft supports a series of pattern chains such as 4, corresponding in number to the harnesses employed and of usual construction, such chains being 90 provided at the desired intervals with indicating lugs such as 5. A transversely extending shaft 6 is mounted at a convenient point relatively to the loom mechanism, such shaft forming an element of an electrical 95 circuit which will be described in greater detail hereinafter, such circuit comprising the conducting wire 7 leading from one pole of a suitable source of electrical energy such as the dynamo 7a. 200 represents one of a series of lever arms corresponding in number to the several harnesses employed in the loom, each lever arm being provided, if desired, with a series of notches 201 with which

2
may be selectively engaged connector elements such as 202 which lead to the corresponding harness, and by means of which the lever members 200 and harnesses are actuated in time with one another.

5 A magnet 203 arranged at a convenient point is provided with an armature 204 which carries a contact element 205 adapted to make contact with an opposed element 206. The contact members 205 and 206 respectively, form a make-and-break device for a circuit comprising wires 207, 208, respectively, forming a portion of the stop motion circuit of the loom and so arranged that 10 upon contact of the members 205, 206, such circuit will be closed and the stop motion mechanism energized to stop the loom. While as herein disclosed the armature 204 serves to initiate the operation of an electrical stop motion it is evident that it might equally well be employed for determining the operation of a mechanical stop motion if desired.

15 Mounted upon a suitable support 21 are a series of signaling devices such as the incandescent lamps 22, 22^a, 22^b, etc. corresponding to the several harnesses employed. A conductor wire 12 leads from the other pole of the dynamo 7^a and is provided with a 20 series of branches 12^a, 12^b, 12^c, etc. leading respectively to a terminal of each of the several lamps. From the other terminals of the lamps extend conductors 27, 27^a, 27^b, etc. which terminate in switch elements 26, 26^a, 26^b, arranged upon the support 21 and preferably directly above and corresponding to the lamps 22, 22^a, etc. Cooperating with the several switch elements 26, 26^a, etc. is a long 25 knife switch blade 25, having a handle 24 whereby it may be actuated, such blade being pivoted upon the support 21 and serving simultaneously to make connection with and between the several switch elements. From the pivotal end of such knife switch extends 30 a conductor 31 connecting with one terminal of the coil of magnet 203. From the opposite terminal of such coil extends a conductor 32 which is electrically connected to the conductor 12 at a point in the latter beyond 35 the endmost of the branches 12^a, etc.

40 Mounted upon shaft 6 are a series of lever members 8, 8^a, 8^b, etc. corresponding in number to the several harnesses and arranged in the vertical planes of motion of the respective pattern chains 4. With this arrangement the pattern lugs 5 serve to swing the levers 8 in a vertical plane, such levers dropping in the absence of a lug and being lifted as a lug passes beneath the same. The 45 levers 8, etc. form switch blades of knife type which cooperate with pairs of separated switch elements 9—13; 9^a—13^a; 9^b—13^b; etc. mounted upon suitable supports such as 10 and 14 respectively, it being understood that 50 such supports extend transversely of the

mechanism and have mounted thereon the switch elements corresponding to each of the several switch blades 8.

Upon the back side of the support 21 are arranged a series of pairs of separated 70 switch elements 19—20; 19^a—20^a; 19^b—20^b, etc. and upon a parallel support 17 are mounted corresponding pairs of separated switch elements 15—16; 15^a—16^a; 15^b—16^b, respectively. A shaft 35 is arranged transversely of the mechanism at a point substantially midway of the supports 21 and 75 17, and upon said shaft are pivotally mounted a plurality of switch levers as 18, 18^a, 18^b, etc., such levers corresponding in number to 80 the several harnesses employed. These levers are preferably provided at their lower ends with yoke-like members comprising spaced arms 18^m, 18ⁿ, respectively, which 85 embrace the upper end of the corresponding lever member 200, whereby the levers 18 are actuated in consonance with the oscillation of the members 200.

90 The levers 18 are provided with oppositely directed blade portions 18^c, 18^d, respectively, such portions being adapted to connect the switch elements 15—16; 19—20, etc. respectively, in accordance with the position of the member 18. The devices are so arranged that upon forward swinging of the lever 95 member 200, the switch elements 19—20, are electrically connected while upon rearward movement of the member 200 the switch elements 15—16, are electrically connected.

100 Extending from the several switch elements 9, 9^a, etc. to the corresponding switch elements 16, 16^a, etc. are the conductors 11, 11^a, 11^b, etc. The corresponding elements 13 and 19 are also connected by 105 conductors 29, 29^a, 29^b, etc. From the several members 15 extend conductors 28, 28^a, 28^b, etc. which are electrically connected with the lamps 22, 22^a, 22^b, respectively, and with the corresponding switch terminals 26, 26^a, 26^b, etc. 110

115 In the normal operation of the device, it being assumed that the armature 204 of the stop motion device is in the position indicated in Fig. 1, and that the knife switch 24 is in position to connect the several switch terminals 26, 26^a, etc., upon proper operation of the harnesses the members 200 will be swung backwardly and forwardly, thus carrying the switch blade elements 18^c, 18^d, 120 respectively, alternately from the members 15—16 etc. to the members 19—20, etc. At the same time, by the rotation of the pattern shaft 3, the several switch levers 8 are caused to rise and fall. The parts are so 125 constructed and arranged, however, that when the harnesses are functioning properly the blades 8 will contact of the switch elements 9 simultaneously with the contact of the switch levers 18, with the elements 19, 130

20, and so that upon contact of the blades 8 with the elements 13, the blades 18^c will contact with the switch elements 15, 16. As thus arranged the normal movements of the 5 levers 18 and 8 prevents the closing of the circuits comprising the lamps 22, and the magnet 203.

If, however, one of the harnesses should fail to function at the proper time, as for 10 example, that harness corresponding to the switch blade 18 in the diagrammatic views Figs. 3 and 4, the circuit between the members 15, 16 may be closed simultaneously with its closing between the members 8 and 15 9. In such case current will flow through the conductors 7, shaft 6, lever 8, the switch element 9, the conductor 11, switch element 16, lever 18, switch element 15, the conductor 28, the lamp 22, and back through the 20 conductor 12. At the same time current will flow from the conductor 28 through the conductor 27, through the switch element 26, the switch blade 25, the conductor 31, the magnet coil 203 and back through the 25 conductor 32 to the conductor 12. Thus the magnet coil will be energized, the armature 204 will be attracted thereto, and the circuit comprising the wires 207, 208 will be energized, whereby to actuate the loom stop motion. 30

At the same time current will flow through the knife switch blade 25 and the other switch terminals 26^a, 26^b, etc. back through the wires 27^a, 27^b, and the lamps 22^a, 22^b, 35 to the conductor 12. Thus all of the lamps will be caused to glow. After the stopping of the loom, however, the operator, by opening the switch comprising the blade 25, will break the circuit through the lamps 22^a, 40 22^b, etc., permitting current to flow only through the lamp 22 and thus indicating that one of the harnesses which is out of order. Upon repairing such harness, the operator will replace the knife switch 25 45 and upon proper operation of the loom the circuit will be kept open by the orderly movements of the members 18 and 8 until in the further operation of the loom one or another of the harnesses fails properly to 50 act whereby to move a lever 18 in proper timed relation to a lever 8.

If, instead of closing the circuit, as above described, it should in an untimely manner be closed between the elements 19, 20, the 55 movement of the lever 8 into contact with the switch element 13 will cause a similar actuation of the stopping and signaling devices. In such a case, current will flow from the wire 7, shaft 6 and lever 8 into the 60 switch element 13 thence through the conductor 29 to switch element 19. From this point current passes through the switch lever 18 to the switch element 20, thence through the conductor 30 to conductor 27, 65 from which the current branches, a portion

passing through lamp 22 and back through the wire 12 while another portion passing through the switch blade 25 energizes the magnet 203, and thence returns through the conductor 22, the operation being in other 70 respects similar to that previously outlined.

In order to avoid confusion in the diagrammatic views, and in view of the difficulty of properly indicating the switch mechanism therein, the circuit including the 75 switch elements 13, the conductor 29 and the elements 19, 20 has been shown in dotted lines.

It is thus evident that simple and effective means has been provided whereby, not 80 only to stop the loom upon failure of any of the several harnesses to function properly, but also whereby the particular harness may be indicated with certainty after the stopping of the loom. While in the 85 above description particular reference has been made to the failure of the single harness corresponding to the blade 18 to function, it is evident that a similar operation would take place when any of the other 90 harnesses should so fail to act, the corresponding circuits being formed in such eventuality.

Moreover, while the pattern chain 4 has been illustrated as provided with pattern 95 lugs 5 at regular intervals, it is to be understood that such chain will, in practice, be furnished with lugs at desired points in accordance with the particular harness pattern employed, the arrangement in all cases 100 being such as to provide for swinging the lever 8 in properly timed relation to the corresponding lever 200.

I claim:

1. A mechanism for use with a loom having a plurality of harnesses and a stop motion, and comprising a signal device corresponding to each of such harnesses, and means automatically operative upon failure of a harness properly to function for actuating said stop motion and for energizing the corresponding signal device. 105

2. A mechanism for use with a weaving loom provided with a stop motion, comprising an oscillatable element having connection to a loom harness and movable in time therewith, a pattern drum, a lever member oscillatable by said drum, and means controlled by the conjoint action of said element and lever whereby to determine the 115 120 action of said stop motion.

3. A mechanism for use with a weaving loom provided with a stop motion comprising an electrical circuit including a stop motion actuator, said circuit having a pair 125 of gaps therein, independent devices for closing said gaps, and means for normally actuating said devices in alternation, the parts being so constructed and arranged that upon failure of said means to actuate one of 130

said devices in properly timed relation to the other, the circuit will be closed and the stop motion actuated.

4. A mechanism for use with a loom having a stop motion, an electrical circuit including a stop motion actuating magnet, a pair of circuit closing switches in said circuit, means actuated by a harness for normally opening and closing one of said switches, and pattern means normally operative to open and close the other switch in alternation to the movement of the first switch.

5. A mechanism for use with looms having a plurality of harnesses comprising a plurality of electrical circuits each including a signal device, a magnet common to all of said circuits, means actuatable upon failure of either of said harnesses properly to function for energizing all of said signal devices and said magnet, and means for simultaneously cutting out all of said signal devices except that corresponding to the defectively acting harness.

6. A mechanism of the class described comprising a harness actuated member, an electrical circuit, a circuit making and breaking device oscillatable by said member, a second circuit making and breaking device, means for normally actuating said latter device in alternation with said first device, and a signaling device in said circuit, the parts being so constructed and arranged that upon failure of said harness actuated member properly to actuate its circuit breaking device, the signaling device will be energized.

7. A mechanism for use with a loom provided with a plurality of harnesses and a stop motion, comprising a signal lamp corresponding to each of said harnesses, a magnet having an armature actuatable for operating the stop motion, electrical conducting means, means operative upon failure of a harness properly to function for permitting current to flow in said conducting means and through said lamps and magnet, and a manually actuatable switch for simultaneously cutting off current from all of said lamps except that corresponding to the defective harness.

8. A mechanism of the class described for use with a loom having a plurality of pattern controlled harnesses and a stop motion, an electrical circuit comprising a device for initiating actuation of said stop motion, said circuit having a plurality of parallel branches corresponding respectively to the

several harnesses, a pair of switch devices in each of said branches, a pattern device for controlling the opening and closing of one switch of each of the several pairs, and connections from each harness to the other and corresponding switches of the several pairs.

9. In combination with a loom having a stop motion and a plurality of harnesses operable in predetermined sequence, a pattern device, and means operable by the joint action of a harness and said pattern device whereby to render such stop motion effective for stopping the loom upon the failure of such harness to perform its normal shedding function.

10. A mechanism for use with a loom having a stop motion and a harness actuated element, comprising a member actuatable by said element in timed relation to the movement of the harness, a pattern controlled device, and means conjointly controlled by said member and said device and operable upon abnormal functioning of the harness to make such stop motion operative.

11. An automatic harness device, comprising electro-mechanical means, spaced terminals in a normally open circuit with said means and a source of electrical energy, and an element movable by a harness when the latter is out of order to a position to electrically connect said terminals, in combination with a pattern, a movable conductive element controlled by the pattern, and terminals complementary to said conductive element and electrically connected, substantially as specified.

12. An automatic stop motion for looms, comprising a pattern, a harness operating arm or lever, electro-mechanical stop motion means, pairs of switch members, a swinging member operable by said arm or lever and adapted in one position to electrically connect the switch members of one pair and in another position to electrically connect the switch members of the other pair, electrical connections between said switch members and the stop motion means, a third pair of switch members, a source of electric energy, a conductive member movable by the pattern into contact with the last-named switch members alternately, an electrical connection between said conductive member and the source of energy, and an electrical connection between the source of energy and the stop motion means.

Signed by me at Lawrence, Massachusetts, this 11th day of June, 1923.

SEBASTIANO MAGNANO.

Certificate of Correction.

It is hereby certified that in Letters Patent No. 1,534,127, granted April 21, 1925, upon the application of Sebastiano Magnano, of Lawrence, Massachusetts, for an improvement in "Harness Stop and Signal Devices for Looms," an error appears requiring correction as follows: In the grant and in the heading to the printed specification the domicile of the assignee is erroneously given as "Essex, Massachusetts," whereas said domicile should have been given as *Lawrence, Massachusetts*, as shown by the records of assignments in this office; and that the said Letters Patent should be read with this correction therein that the same may conform to the record of the case in the Patent Office.

Signed and sealed this 26th day of May, A. D. 1925.

[SEAL.]

KARL FENNING,
Acting Commissioner of Patents.
